UNITED STATES PATENT OFFICE

CHRISTOPHER M. CORDLEY, OF NEW CANAAN, CONNECTICUT, ASSIGNOR TO CORDLEY
& HAYES, OF NEW YORK, N. Y., A CORPORATION OF NEW YORK

DESIGN FOR A BEVERAGE-DISPENSING APPARATUS

Application filed February 21, 1929. Serial No. 30,169. Term of patent 7 years.

To all whom it may concern:

Be it known that I, CHRISTOPHER M. CORDLEY, a citizen of the United States, residing at New Canaan, in the county of Fairfield and State of Connecticut, have invented a new, original, and ornamental Design for Beverage-Dispensing Apparatus, of which the following is a specification, reference being had to the accompanying drawing, forming a part hereof.

The figure of the drawing is a perspective view of a beverage dispensing apparatus showing my new design.

I claim:

The ornamental design for a beverage dispensing apparatus, as shown.

CHRISTOPHER M. CORDLEY.
